UNITED STATES PATENT OFFICE.

JEREMIAH A. SCRIVEN, OF NEW YORK, N. Y.

DESIGN FOR A BIFURCATED NETHER GARMENT.

SPECIFICATION forming part of Design No. 31,661, dated October 10, 1899.

Application filed September 16, 1899. Serial No. 730,772. Term of patent 14 years.

To all whom it may concern.

Be it known that I, JEREMIAH A. SCRIVEN, a citizen of the United States, residing in the borough of Manhattan, city, county, and State of New York, and whose post-office address is No. 18 East Fifteenth street, in said city, have invented and produced a new and original Design for Bifurcated Nether Garments, of which the following is a specification.

10 The characteristic features of my design consist in two separate insertions in the rear of the garment, which insertions each extend in a continuous length substantially throughout the length of the garment, and which insertions are separated by an interposed panel.

In the accompanying drawing the figure represents a rear view of a bifurcated nether garment embodying my design.

Referring to the drawing, A indicates the

1 rear of the body portion of the garment, from which project tubular members B. Extending in a continuous length throughout each of the tubular members and throughout the rear of the body portion of the garment to substantially the upper end thereof is an insertion a, which has ribs or wales b extending continuously in a longitudinal direction throughout the length thereof. These insertions a are separated in the seat of the garment by an interposed panel c.

20 25 30 What I claim is—

The design for a bifurcated nether garment substantially as herein shown and described.

JEREMIAH A. SCRIVEN.
